UNITED STATES PATENT OFFICE

LE ROY W. WILLIS, OF BROOKLYN, NEW YORK, ASSIGNOR TO INTERTYPE CORPORATION, OF NEW YORK, N. Y., A CORPORATION OF NEW YORK

THERMOSTATIC CONTROL DEVICE

Application filed March 1, 1929. Serial No. 343,848.

The present invention relates to improvements in thermostatic control means and more especially to thermostatic control means for regulating the supply of heat energy to the metal pots of commercial type casting machines and particularly to machines of this class which cast type bars or slugs, an example of a machine of this class being shown and described in U. S. Letters Patent

10 No. 436,532 granted September 16, 1890 to O. Mergenthaler.

In the operation of typographical machines of this class, the type metal from which the type bars or slugs are cast, is maintained in a molten condition at a temperature of between 525° and 550° F. Gas or electricity is usually employed as the source of heat energy, the metal pot being provided with a gas burner or an electric heating element

20 for heating it, and a thermostat is necessary to regulate the supply of gas or electricity.

It has been found desirable however to provide or employ a control device which is capable of governing the supply of gas and of electricity either concurrently or separately, whereby the control device may be applied universally to a metal pot which is heated either by a gas burner or by electrical heating means and moreover, it may be applied

30 to a metal pot which is heated both by gas and electricity, in which instance, a single control device may be utilized to govern concurrently the supply of gas and electricity to the metal pot.

35 The primary object of the present invention is to provide a novel and improved automatic temperature control device which is capable of governing the supply of gas and electricity, either separately or simultaneously to the metal pot of the type casting machine for heating the metal pot.

Another object of the invention is to provide a device of this character wherein the

40 means for controlling the supply of the different forms of heat energy coact and are operative from a single thermostat.

45 A further object is to provide a device of this character wherein the supply of heat from one source may be regulated and ad-

justed independently of the supply of heat energy from the other source.

To these and other ends, the invention consists in certain improvements and combinations and arrangements of parts, all as will be hereinafter more fully described, the features of novelty being pointed out particularly in the claims at the end of the specification.

In the accompanying drawings:—

Fig. 1 is an elevation of a thermostatic control device adapted for use in connection with the metal pot of a typographical machine and embodying the present invention, the front or cover plates of the device being removed;

Fig. 2 represents a vertical cross section taken on the line 2—2 of Fig. 1 and looking toward the right;

Fig. 3 is a view similar to Fig. 1 but showing the heat energy control devices in their two extreme positions by their full and dotted lines respectively; and

Fig. 4 represents a horizontal cross section taken on the line 4—4 of Fig. 1 and looking downwardly, the cover plate being shown in place.

Similar parts are designated by the same reference characters in the different figures.

Automatic control devices embodying the present invention are applicable to various uses where it is desirable or necessary to maintain a medium at a substantially constant predetermined temperature by regulation of the supply of heat energy thereto; al-

though the invention is more particularly applicable to the metal pots of typographical machines for the purpose of maintaining the molten metal at a substantially constant predetermined temperature in order to effect effi-

cient operation of the casting mechanism and especially to insure the production of type or type bars or slugs which will be free from imperfections, or substantially so. The pre-

ferred embodiment of the invention is shown in the accompanying drawing and will be hereinafter described in detail, but it is to be understood that the invention is not restricted to the precise construction shown since equivalent constructions may be used

and such will be included within the scope of the claims.

The automatic temperature control device, as shown in the present instance, comprises 5 generally a gas governor A and electrical control means B, these elements of the device being combined as a unit and controlled by a single or common thermostat.

The gas governor as shown is similar, in 10 its construction and mode of operation to that disclosed in U. S. Letters Patent No. 1,210,045, granted December 26, 1916 to M. Butts, it being believed sufficient for the present purposes to describe the gas governor as 15 comprising a casing 1 having an interior chamber the front of which may be closed by a removable cover 2, one wall of the casing having a groove 3 therein one end of which is in communication with an inlet pipe 4 through which illuminating or other combustible gas for the gas burner of the metal pot is supplied, the side of the casing beyond the groove 3 having an outlet 5 which serves to conduct the gas admitted by the gas 20 governor to the gas burner of the metal pot. The interior chamber of the casing 1 contains a valve 6 which has a face which is adapted to seat against the side of the casing 1 which surrounds the groove 3 therein, one end of 25 this valve having a lug 7 fixed to it and projecting therefrom in a direction which is at an angle to the plane of the seat engaging face of the valve. One end of the valve is arranged to abut against the inner end of an 30 adjustable screw 8, this screw serving to limit the movement of the valve in one direction and providing a fulcrum on which the valve may rock toward seated and unseated position with respect to the side of the casing in 35 which the groove 3 is formed, the valve being so constructed that when it is fully seated flatwise against the portion of the side of the casing which contains the groove 3, the admission of gas to the interior of the casing 40 through the inlet 4 is cut off, and when the valve is rocked more or less in a direction away from the side of the casing containing the groove 3, gas may flow from the inlet 4 into the groove 3 and from the latter into the 45 interior chamber of the casing, and the gas thus admitted to the chamber may flow out through the outlet 5 and thus pass to the gas burner of the metal pot, which may be of the usual or well known construction. A pilot 50 light screw 9 is preferably threaded through the side of the casing in which the groove 3 is formed and this screw is adjusted so that its inner end will engage the valve 6 and thereby prevent complete seating thereof, so that a small flow of gas is allowed to 55 pass through the governor under conditions where the automatic control means would otherwise cause complete closing of the valve and cutting off of the gas supply, the pilot 60 screw thus allowing the flow of a sufficient 65

amount of gas to the burner to maintain a small or pilot light. The valve 6 is yieldingly urged toward its seat by a spring 10.

The thermostat for the gas governor, which also serves to govern the operation of the electric control means, may be of different forms, the thermostat shown comprising a sleeve 11 composed of a metal or material having a relatively high coefficient of expansion, this sleeve being threaded or otherwise secured 70 in the bottom of the casing 1 of the gas governor and being of suitable size and length to be immersed in the molten metal contained in the metal pot, and the other element of the thermostat comprises a rod 12 which is composed of a metal or material having a relatively low coefficient of expansion, the upper end of this rod abutting pivotally against the under side of the lug 7 as at 13 on the valve and the lower end of this rod abutting against a 75 suitable seat 14 formed within the sleeve 11 near the lower end thereof. In operation, the valve 6 will be moved toward or from its seat by the differential expansion and contraction of the sleeve 11 and rod 12 which 80 form the temperature responsive elements of the thermostat. At temperatures below the predetermined or normal operating temperatures, the sleeve 11 and the rod 12 will be relatively contracted, and since the sleeve 11 85 will be contracted to a greater extent than the rod 12, the rod 12 will be forced bodily upwardly by reason of its engagement with the lower end of the sleeve 11 and, in consequence, the lug 7 of the valve will be acted 90 on in a manner which will force the upper end of the valve against the lower end of the screw 8 and to cause the valve to rock about the lower end of the screw 8 as a fulcrum, 95 into a more or less unseated position; and when the temperature is at or above the predetermined or normal temperature at which the molten metal in the metal pot should be 100 maintained, the sleeve 11 will be expanded to a degree which will bring the rod 12 into 105 a bodily lowered position, in consequence of which the valve will be moved toward seated position under the influence of the spring 10. During the normal operation of the device 110 as applied to the metal pot of a typographical machine, a drop in the temperature of the molten metal in which the sleeve 11 is immersed will cause contraction of this sleeve 115 in consequence of which the valve 6 will be moved to a further opened position, and an increase in the temperature of the molten metal will cause expansion or lengthening of the sleeve 11, in consequence of which the valve 6 will be caused to move toward seated 120 position. Temperature variations of the molten metal in which the sleeve 11 is immersed will therefore bring about automatically an increase or a decrease in the volume 125 of gas flowing to the burner of the metal pot, in accordance with a drop or an increase in 130

the temperature of the molten metal, and an approximately constant temperature of the molten metal may thus be maintained, the screw 8 being adjusted to set the governor to 5 maintain the particular temperature desired.

The electric control means for automatically governing the supply of electric current to the metal pot to heat it, comprises a casing 15 which may, as shown, be formed 10 separately from the casing 1 of the gas governor but may be rigidly secured to a side thereof by screws 16 or other suitable means. Within this casing is mounted a tube 17 preferably of glass and evacuated of air, the 15 tube being elongated in form and having electric terminals or electrodes 18 and 19 sealed or otherwise fitted into one end thereof, the tube also containing a body 20 of metallic mercury which partially fills the 20 tube so that the terminals or electrodes 18 and 19 will not be bridged by the mercury when the tube is in its normal or substantially horizontal position. The electrodes 18 and 19 in the tube are connected by flexible wires or other suitable conductors 21 and 22 to binding posts or terminals 23 and 24 which are mounted in a suitably insulated manner upon the casing 15, it being understood that the electric heating circuit for 25 the metal pot is connected to these binding posts and that the closing of the electric heating circuit is controlled by the electrodes 18 and 19 and the body of mercury 20.

The tube 17 is supported, preferably removably, by a yoke-shaped clip 25 which is 30 rotatably mounted on a pivot pin or stud 26 which is secured in fixed position in the back of the casing 15, the yoke being removably retained on the pivot pin 26 by a slotted 35 washer 27 which removably engages a groove in the periphery of the pivot pin 26, or a cotter pin or other suitable means may be employed for retaining the yoke 25 on the pin 26. This pivotal mounting of the yoke 25 40 and the tube 17 carried by it, on a horizontal axis, enables the tube to be rocked in a direction which will raise or lower either end thereof, and when the end of the tube containing the electrodes 18 and 19 is lowered 45 to a sufficient degree by the rocking of the tube, the body of mercury 20 which flows to the lower end of the tube, will cover both of the electrodes 18 and 19 as shown by the full lines in Fig. 3 and it will thereby complete an 50 electric circuit between these electrodes, and when the tube occupies an approximately horizontal position as shown in Fig. 1 or an oppositely inclined or rocked position as indicated by the dotted lines in Fig. 3, the 55 upper electrode 18 or both of the electrodes 18 and 19 will be out of contact with the body of mercury, and in either of those instances the circuit will not be closed through these electrodes.

60 Means is provided whereby the thermostat

which controls the operation of the gas governor will also control the operation of the electrical contact carrying tube 17 to govern the supply of electrical energy for heating the metal pot. In the construction shown, a 65 gear 28 is fixed to the rear side of the yoke or clip 25 so that it will rotate about the pivot pin 26 as an axis, and a lever 29 is pivotally mounted on a pivot pin 30 supported in the lower portion of the casing 15, 70 this lever being removably retained on its pivot pin by a slotted washer 31 similar to the washer 27, or by any other suitable means. The upper end of the lever 29 is formed with 75 a gear segment 32 which meshes with the gear 28 attached to the yoke 25, and the lower end of the lever 29 carries a nut 33 in which a screw or the threaded portion of a rod 34 is threaded, the nut 33 being preferably 80 split as shown and the threaded portion of the rod 34 having a relatively tight fit therein. One end of the rod 34 is provided with a head 35 which is preferably squared or in the form of a nut while the opposite end of the rod 34 extends through a slot 36 formed 85 in the wall of the casing 15 and is provided exteriorly of the casing with a head or handle 37 by means of which the rod 34 may be rotated to adjust it axially with respect to the nut 33. A spring 38 is connected at one end 90 to a wall of the casing 15 and at its opposite end to a lug 39 on the lever 29, this spring acting on the lever 29 to urge it always in 95 a direction which will maintain the face of the head 35 of the rod 34 in engagement with 100 a plunger 40. The plunger 40 provides the connecting or controlling link between the thermostat and the electrical control means, it extending through the walls of the casings 1 and 15 so that it may reciprocate axially 105 therethrough and the opposite end of this plunger being operatively connected to the thermostat preferably by abutting against the free or laterally swinging end of the gas governing valve 6. Since the interior chamber of the gas governor casing 1 contains 110 gas, suitable means is provided to prevent the escape of such gas into the casing 15 containing the electrical control means, a thin flexible metal diaphragm 41 being shown for 115 this purpose in the present instance, the diaphragm being secured at its center to the plunger 40 and being secured at its periphery between suitable washers 42 composed of rubber or other suitable material, the center 120 of the diaphragm being sealed to the plunger and its periphery being sealed by the washers so that the escape of gas along the plunger and into the casing 15 is prevented although the diaphragm will not interfere with free 125 axial movements of the plunger since the diaphragm is free to yield when the plunger is moved axially. The pressure of the head 35 against the plunger 40, under the influence 130 of the spring 38, maintains the opposite end

of the plunger in contact with the gas valve 6, and since the latter is connected to the thermostat by the engagement of its lug 7 with the upper end of the rod 12 which constitutes one element of the thermostat, it will be evident that the lever 29 which controls the position or operation of the circuit controlling tube 17 is under the control of the thermostat. When the thermostat responds to a decrease in temperature, the plunger 40 will, in consequence reciprocate in a direction which causes the lever 29 to swing into the position shown by the full lines in Fig. 3, and this movement of the lever will rock the tube 17 in a direction which will lower its electrodes 18 and 19 and cause them to be covered and hence bridged by the body of mercury 20 which flows to the thus lowered end of the tube, the electric heating circuit of the metal pot being thereby closed, and when the thermostat responds to an increase in temperature the plunger 40 reciprocates in the opposite direction and the lever 29 is swung into the reverse position shown by the dotted lines in Fig. 3, and in consequence the tube 17 is rocked into the reverse position shown in dotted lines in Fig. 3 thus carrying the body of mercury 20 therein away from the electrodes 18 and 19 and the electric heating circuit is thereby broken. In Fig. 1, the parts are shown in the positions which they occupy when the thermostat is subject to the influence of a predetermined temperature which is maintained by the flow of gas to the gas burner of the metal pot as permitted by the partially open gas control lever 6, the tube 17 containing the electrodes occupying a position midway between its fully on and fully off positions and the electric heating circuit for the metal pot being broken since the electrode 18 is out of contact with the body of mercury 20.

When the automatic temperature control device is used in connection with a metal pot which receives its heat from a gas burner alone, the temperature of the metal in the pot will be maintained substantially constant by the gas governor, its valve being automatically opened wider as the temperature of the metal in the pot diminishes and being moved toward closed position to diminish the supply of gas to the burner when the temperature of the metal drops, and while the temperature of the metal in the pot remains substantially stationary, the gas control valve of the gas governor will be automatically maintained in a partially opened position where sufficient gas will flow to the burner to maintain such temperature.

When the automatic temperature control device is used with a metal pot which is heated by electric current, the temperature of the molten metal in the pot is automatically maintained substantially constant by the governing of the supply of electric current

to the metal pot by the electric controller which is controlled by the thermostat. In this instance, should the temperature of the molten metal in the metal pot drop, the thermostat will operate to rock the circuit controlling tube into a position to close the electric heating circuit through the electrodes in the tube, and should the temperature of the molten metal rise above a predetermined point, the thermostat will operate to rock the circuit controlling tube into a position where the electric heating circuit is broken by the movement of the body of mercury in the tube out of contact with one or both of the electrodes, and by the alternate opening and closing of the electric heating circuit under the control of the thermostat, the temperature of the metal may be maintained substantially constant by the electric heating means for the metal pot.

In using the automatic temperature control device in connection with a metal pot which is heated by both gas and electric current, the thermostat will act, upon a drop in temperature of the molten metal, to cause increased opening of the gas control valve and rocking of the circuit controlling tube in a direction which will cause closing of its electrodes whereby electric heating current will be supplied to the metal pot, and upon a rise in temperature of the metal above a predetermined point, the thermostat will act to cause movement of the gas control valve toward closed position to reduce the supply of gas to the burner and it will concurrently cause rocking of the electric control tube in a direction to open the electric heating circuit and thereby cut off the supply of electric heating current to the metal pot. In the particular adjustment of the parts as shown, the gas control valve may normally supply sufficient gas to the burner to maintain the molten metal in the metal pot at the predetermined normal temperature and the electric controller will act to close the electric circuit and supply electric heating current which will augment the gas heating upon an abnormal or sudden drop in temperature of the molten metal, the electric heating circuit being open however as soon as the temperature of the molten metal has been restored to normal. The adjusting screw 8 enables the gas controller to be set to operate in a manner to maintain any desired temperature of the molten metal, and adjustment of the threaded rod 34 of the electric controller enables the latter to be correspondingly adjusted to compensate for adjustments of the gas controller as made by the screw 8, or to set the electric controller to open and close the electric heating circuit under different temperature conditions to which the thermostat responds.

A combined gas governor and electric controller as hereinbefore described is applicable

universally to the metal pots of typographical machines which are heated either by a gas burner or by electrical heating means alone, thus rendering it unnecessary to provide a special temperature control device to be employed in each instance, and it is also applicable to metal pots which are heated both by a gas burner and by electrical heating means, the dual control of both sources of heating energy by the single device and from a single or common thermostat enabling the temperature control device to be applied with facility to the metal pot, notwithstanding the limited space usually available, and when so used, greater uniformity in the temperature of the molten metal is insured since the heating effect of both the gas burner and the electrical heating means will be increased when a sudden reduction in temperature of the molten metal occurs as when fresh metal is added to the metal pot, and the heating effect of both the gas burner and the electrical heating means is reduced or interrupted when the temperature of the molten metal rises.

Furthermore, when both gas and electricity are used as sources of heat energy, the adjusting means hereinbefore described not only enable both of these sources of heat energy to be used concurrently but the control means for the electric current supply may be so adjusted that it will normally or whenever desired, interrupt the supply of electric heating current while the gas control means continues to function in a manner to supply gas to maintain the desired temperature of the metal pot, so that while both sources of heat may be used to heat up the metal pot from a cold start, one of the sources of heat energy may be cut off entirely during the operating hours of a day, thus economizing in operating cost.

I claim as my invention:—

1. An automatic temperature control device for the gas heated or electrically heated metal pot of a typographical machine comprising, in combination a thermostat responsive to the temperature of the metal in the metal pot, a gas governor for governing the supply of gas to such metal pot, an electric circuit controller for governing the supply of electric heating current to such metal pot, and means for controlling the gas governor and the electric circuit controller from said thermostat.

2. In a thermostatic control device, the combination with a gas governor having a gas control valve and a thermostat for causing it to open and close in response to temperature changes to which the thermostat is subjected, of an electric circuit controller having a contact controlling member, a connection between said member and valve for causing the electric circuit controller to operate concurrently with the gas governor,

and adjusting means for said connection for varying the temperature responsive relationship of the electric circuit controller with respect to the gas governor.

3. In a thermostatic control device, the combination with a gas governor embodying a gas control valve, a thermostat for causing it to open and close in response to temperature changes to which the thermostat is subjected, and adjusting means for varying the temperature responsive relationship of said valve with respect to the thermostat, of an electric circuit controller embodying a circuit controlling member, and a connection between said member and said valve for causing operation of the electric circuit controller concurrently with the gas governor, said connection having means for adjusting it to compensate for adjustments of the adjusting means for the valve of the gas governor.

In testimony whereof I have hereunto set my hand.

LE ROY W. WILLIS.
